BATTERY CHARGING UNIT

Peter T. Quinn, Littleton, Colo., assignor to
Honeywell Inc., Minneapolis, Minn.

Original design application June 6, 1969, Ser. No. 17,555,
Now Patent No. 219,031, dated Oct. 27, 1970. Divided
and this application Mar. 17, 1970, Ser. No. 21,932

Term of patent 14 years

Int. Cl. D13—02

U.S. Cl. D26—15

FIG. 1

FIG. 2

FIG. 3

FIG. 1 is a perspective view of the front and one side of a battery charging unit in accordance with the present invention;

FIG. 2 is a top plan view thereof; and

FIG. 3 is a bottom plan view thereof.

The back and remaining side of the unit are identical to the front and one side, respectively, shown in FIG. 1.

This application is a division of design patent application Serial No. D-17,555, filed June 6, 1969, and now Patent No. Des. 219,031.

I claim:

The ornamental design for a battery charging unit, as shown and described.
